PRINTER'S MITER GAUGE

Claude Fogle Hanlon, Wewahitchka, Fla.

Application January 4, 1937, Serial No. 119,030

5 Claims. (Cl. 164—10.5)

The present invention relates to certain new and useful improvements in printers' miter gauges, of which the following is a specification.

In the art of printing, as is well known it is frequently necessary to cut leads, borders, or slugs of proper lengths, as well as with accurately mitered ends in order to form square borders.

While devices of this character have heretofore been proposed and used, those which performed the work accurately and expeditiously were of more or less complicated construction and, accordingly, were too expensive to be within reach of the average small printing shop.

15 A primary object of the present invention is the provision of a miter gauge, which is simple in construction, accurate in operation, and which can be manufactured and sold at relatively low cost.

20 A further object of the invention is the provision of a miter gauge, which is of such construction that it can be readily secured in operative position on any hand rule and lead cutter, as well as on bench saws.

25 A still further object of the invention is the provision of a miter gauge having a scale for determining the lengths of the borders or slugs to be cut and comprising effective slug-holding means so disposed as not to obscure visibility of the scale.

30 With the above objects in view, as well as others that will become obvious during the course of the following disclosure, reference will be made to the accompanying drawing forming part of the same, and wherein:—

35 Fig. 1 is a perspective view of a lead cutter having operatively attached thereto a preferred embodiment of my invention;

Fig. 2 is a perspective view of my improved 40 device in a preferred embodiment thereof;

Fig. 3 is a transverse sectional view in a plane indicated by the line 3—3 in Fig. 2;

Fig. 4 is a transverse sectional view in a plane indicated by the line 4—4 in Fig. 1; and

45 Fig. 5 is a side elevational view of a modified form of my invention.

Referring to the drawing in detail, and wherein like reference characters designate like parts, A designates a cutting machine of a well-known 50 design, having a bed plate B and a cutting knife C, adapted to be oscillated about the shaft D by means of a handle E, and the connecting links F. This machine forms no part of the present invention but is shown only to illustrate the manner of attaching and using my improved miter

gauge in connection with any well-known or existing machine.

My improved miter gauge consists essentially of a substantially triangular frame, including a horizontal base member 10, a vertical upright 11, and an inclined work-supporting member 12. This triangular frame may be constructed of wood or metal but preferably is formed from a single unitary piece of sheet metal of the appropriate width and bent into triangular form 10 with the ends suitably joined, as by welding, preferably at one of the apices of the triangle.

5 Detachably secured to the base member 10, as by screws 13, is one leg 14 of a U-shaped bracket 15, the opposite leg 16 of which is disposed below 15 the base member 10 at a substantial distance for providing a channel for receiving the bed plate B, as is indicated in Fig. 1.

Threadedly engaged within a tapped aperture 17 in the leg 16 is the threaded portion of a thumb screw 18, whereby the base member 10 may be rigidly clamped on the bed plate B by turning the thumb screw 18 upwardly into binding engagement with the bottom of the bed plate B when the miter gauge has been properly positioned thereon relative to the cutting knife C, as indicated in Fig. 1.

20 While the bracket 15 may be permanently secured to the base member 10 if desired, it is preferably removably secured thereto as above disclosed in order that it may readily be removed if it should be desired to use the device on a lead cutter having a bed plate of such thickness that the channel in the bracket 15 will not receive it or should it be desired to attach the device on a 25 printer's bench saw, which does not have the mitering feature.

30 Suitably secured to one edge of the inclined member 12 is a plate 19, which, in the preferred embodiment of the invention, includes lugs 21 and 22 at opposite ends thereof and which are interconnected by a rod 23 in spaced relation to an edge 24 of the plate, which edge extends above the outer surface of the inclined member 12 for providing, in cooperation with the lugs 21 and 35 22, an edge guide for the slugs or borders to be mitered.

35 Loosely supported on the rod 23 by means of a sleeve 25 for both pivotal and slidable movement relative to the rod is a block 26, to the bottom of which is suitably secured a slug-engaging rubber pad 27, the sleeve 25 being preferably formed by the intermediate portion of a rectangular metal strip, whose opposite ends are in face-to-face contact and suitably secured to the 40 45 50 55

block 26 and between same and the rubber pad 27.

The inclined member 12 is provided with a scale 28 adjacent the edge thereof opposite the edge to which the plate 19 is secured, and which scale preferably is graduated to designate picas and half picas for accurately indicating desired lengths of slugs to be mitered.

In operation of the improved miter gauge, it is secured to the bed plate B of a lead cutter in the manner above-described and as is illustrated in Fig. 1, with the apex edge at the junction of the base member 10 with the inclined member 12 in proper position with respect to the cutting knife C. A slug is then placed on the inclined work-supporting member 12 with one edge thereof in contact with the edge guide 24 on the plate 19, whereupon the block 26 is moved axially of the rod 23 to a position depending upon the length of the slug and is then pivotally moved on the rod to bring the rubber pad 27 into effective gripping contact with the slug to hold the same in accurately fixed position by the left hand of an operator, who, with his right hand, will operate the handle E for forming a miter cut on the end of the slug adjacent the knife C.

As is more clearly indicated in Fig. 4, the rod 23 is so disposed that the block 26, when in slug-engaging position, extends slightly downwardly at an angle to the surface of the member 12, whereby upon pressure being applied to the block, the rubber pad 27 will not only exert pressure in a vertical direction on the slug, but a component of the pressure will be exerted in the direction of the edge guide 24, and the slug will be accurately held in position on the surface of the member 12 and on the surface of the edge guide 24.

It is to be particularly noted that the block 26 and scale 28 are so disposed that when pressure is being exerted on the block by the left hand of an operator, the scale will not be obscured from vision, whereby the operator can readily ascertain the length of slug which he desires to cut.

In Fig. 5 is illustrated a modified embodiment of my invention, wherein the triangular frame 10^a is solid and wherein the block 26 is secured to plate 19 by hinges 30, whereby the block will have a pivotal movement only. This arrangement will be highly satisfactory on fixed length slugs, but when cutting slugs of various lengths, the first form of the invention is preferable, since the block 26 can be moved to most effective gripping positions on the slugs.

When forming the triangular frame solid, as illustrated in Fig. 5, the bracket 15 will be L-shaped, having the shorter leg 31 secured to a face of the frame by screws 32.

While the hinged connection of the block 26 is illustrated in connection with a solid frame, it may be used equally as well with the form of frame illustrated in Fig. 2, and the form of connection of the block 26 illustrated in Fig. 2 may

be used with a solid frame of the form illustrated in Fig. 5.

Having thus explained the nature of the invention and described an operative manner of constructing and using the same, although without attempting to set forth all of the possible modified forms of construction, what I claim as new herein and desire to secure by Letters Patent is:—

1. A miter gauge comprising a triangular frame having a base and an elongated inclined work-supporting surface, a bracket secured to the base for detachably connecting the frame with a cutting machine and with the lower end of the work-supporting surface adjacent the cutting knife, a scale extending lengthwise of the work-supporting surface adjacent one edge thereof, a plate secured to the frame and projecting above the work-supporting surface adjacent the opposite edge thereof for providing a work edge guide, a rod supported by the plate adjacent the upper edge thereof, and a work-engaging and holding member slidably and pivotally connected with the rod.

2. A miter gauge comprising a frame having an inclined work-supporting surface, a plate secured to the frame and projecting above the work-supporting surface for providing a work edge guide, a block pivotally connected with the upper edge of the plate, and a yieldable pad carried by the block for engaging the upper surface of work on the work-supporting surface, the pad when in work-engaging position extending slightly downwardly from the pivotal connection of the block for urging the work into contact with the edge guide.

3. A miter gauge comprising a frame having an inclined work-supporting surface, a rod secured to the frame in parallel relation to the work-supporting surface, and the means pivotally and slidably engaging the rod for engaging and holding work at various positions on the work-supporting surface.

4. A miter gauge comprising a frame having an inclined work-supporting surface, an edge guide adjacent one edge of the work-supporting surface, and a member pivotally connected with the frame above the edge guide for movement toward and from the work-supporting surface and with the said member angularly disposed relative to the work-supporting surface when in engagement therewith for holding work in engagement with the work-supporting surface and the edge guide.

5. A miter gauge comprising a triangular frame having an inclined work-supporting surface, a plate secured to the frame and projecting above the work-supporting surface for providing a work edge guide, a lug at each end of the plate, a rod extending parallel with the work-supporting surface above the work edge guide and having its opposite ends secured to the lugs, and a work engaging block pivotally and slidably connected with the rod.
